UNITED STATES PATENT OFFICE

HARRY N. MIDDLETON, OF WESTVILLE, NEW JERSEY, ASSIGNOR TO B. F. STURTEVANT COMPANY, OF HYDE PARK, MASSACHUSETTS, A CORPORATION OF MASSACHUSETTS

ELIMINATOR

Application filed February 6, 1926. Serial No. 86,474.

The present invention relates to apparatus for removing particles of solid or liquid foreign matter from air currents.

The object of the present invention is to provide a simple yet efficient apparatus by which solid or liquid particles may be eliminated from induced currents of air, which may be readily cleaned after an accumulation of solid or liquid matters thereon, and which is particularly adapted for use where sticky materials, such as paint, are to be removed.

With this object in view the present invention consists in the apparatus hereinafter described and more particularly defined in the claims.

The present invention is herein illustrated and described as embodied in an apparatus for spray-painting metal articles, which operation, owing to the tenacious, adhesive properties of the materials employed, is liable to give rise to excessive accumulations of paint and dust in the exhaust ducts and on the fan, tending to reduce the effective diameter of the air passages and to unbalance the moving parts of the system. The invention comprises essentially an eliminating chamber which includes a mass of material on which the particles of foreign matter may collect while permitting passage of the air current through the exhaust ducts and the fan without excessive obstruction. In order that efficient maintenance of operation may be assured, provision is made for convenient cleaning from the eliminator of accumulations of foreign matter which may collect therein, an operation which, according to the present invention, is facilitated by a construction whereby separate sections or portions of the mass may be readily removed from or replaced in the eliminator, independently of the remainder.

In the accompanying drawings Fig. 1 is a front view of a spray apparatus employed in connection with a spray or dust eliminator embodying the features of the present invention; Fig. 2 is a side elevation of the apparatus shown in Fig. 1; Fig. 3 is a vertical sectional elevation of the spray or dust elimi-

nator, and Fig. 4 is a front sectional elevation of the apparatus shown in Fig. 3.

The illustrated embodiment of the invention comprises a spray booth 6 adapted to contain an article to be spray-painted and having a front opening 8 before which the operator stands to direct a spray of liquid paint into the interior. The booth communicates directly with an overhead exhaust chamber 10 which in turn communicates with an exhaust passage 12 connected to a duct 14. The duct 14 may connect with any number of exhaust pipes 12 for connection with a plurality of spray booths, and an induced draft of air will be created by an exhaust fan or in other convenient manner and of the proper magnitude to convey from the spray booth any particles of dust or liquid spray which may be suspended therefrom.

In order to eliminate from the air current the particles of dust and spray which emerge from the booth 6, there is interposed between the exhaust chamber and the pipe 12 an eliminator chamber 16 enclosing a mass to which the particles of solid and liquid matter may adhere, while providing interstices through which the exhaust air may pass by tortuous paths into the exhaust pipe 12.

According to the preferred form of the present invention, the mass to which the particles of foreign matter adhere comprises a series of staggered rows of depending chains 18. Each row of chains is suspended from a T support 20 and the various T supports are in turn supported by a series of co-operating inverted T irons 22, which are secured by angle irons 24 to the upper part of the framework of the eliminator chamber. The chamber itself is of angle iron construction and has side doors 26, bolted at each side, which may be removed to gain access to the interior. By removing either of the doors 26, access is obtained to the interior of the chamber, so that one or more rows of chains may be readily removed by sliding them outwardly on their supports in an obvious manner. The staggered relation of the various rows of chains is clearly indicated in Fig. 4, which shows in the major portion of the figure the front row of chains, and at the right hand

side of the figure the next successive rows of chains, a portion of the view of the front chains being broken away at this side of the figure.

5 A plurality of upstanding angle irons 30 are secured to the floor of the eliminator chamber and extend upwardly between some of the rows of chains, serving as stops to prevent excessive forward and backward swaying of the chains in the air current. The area of the eliminator chamber is sufficiently 10 larger than the area of the exhaust pipe 12 so as not to cause excessive resistance to the passage of air therethrough.

15 The current of air through the eliminator is broken up into a number of small streams by the deflecting action of the chains, the latter serving to catch any particles of solid or liquid material which may be carried out 20 of the spray booth by the air. The adhesion of the liquid paint to the chains forms a backing to which particles of dust may attach themselves to prevent the passage of either dust or spray into the exhaust pipe 12 where 25 it might accumulate to decrease the effective diameter of the exhaust passage, or be passed on to the fan where it might unbalance the moving parts of the system.

When the chains become covered with a sufficient quantity of residue they may be conveniently removed from the chamber to have the residue cleaned therefrom by burning or by chemical action. The invention provides for convenient independent removal from 35 the chamber of any one or several rows of chains, thus facilitating the cleaning operation.

While the invention has been described as embodied in a spray apparatus it is to be understood that it is not to be so limited but may be employed for use in other systems where particles of solid or liquid material are to be removed from a stream of air. For example, in removing dust from an air current which carries no liquid substance, the chains may be covered with some adhesive compound to which particles of dust may attach themselves while the current of air passes through the exhaust ducts into the 50 fan.

Having thus described the invention, what is claimed is:

1. An eliminator comprising an air passage, a plurality of rows of closely spaced 55 depending chains in the passage, and means for supporting the chains to permit separate removal horizontally of any of the rows of chains as a unit and independently of the remainder.

60 2. An eliminator comprising a chamber adapted to be placed in an exhaust passage, a plurality of spaced inverted T supports secured at the top of the chamber, a plurality of T supports engaging with the inverted 65 supports and adapted to be placed and moved

in the chamber by longitudinal sliding movement, and a plurality of chains depending from each of the removable T supports.

3. An eliminator comprising an air passage, a plurality of depending chains in the 70 passage to intercept particles of foreign matter while permitting the flow of air through the passage, supports for the chains, each support carrying a plurality of chains and being longitudinally removable bodily with 75 the chains attached.

4. An eliminator comprising a chamber adapted to be placed in an exhaust passage, a plurality of rows of closely spaced chains in the chamber to permit the flow of air between the interstices thereof while serving to collect particles of solid or liquid matter, the chains of one row being staggered with respect to the chains in another row, T-supports on which the separate rows of chains 80 are mounted, and means for supporting the T-supports constructed and arranged to permit the removal of one or more rows of chains 85 by a longitudinal sliding movement of the T-support along its supporting means and 90 independently of the remaining supports and rows of chains.

5. An eliminator comprising a casing having an air passage, a plurality of sets of members located in the passage, the members being spaced to provide a multiplicity of 95 passages for the flow of air and serving to collect foreign matter in the air current, supports slidingly mounted in the air passage each support carrying one of the sets of members pivoted therein, a series of stops for the lower ends of the members and extending transversely of the passage to prevent excessive forward and backward swaying of 100 the members, the casing having provision for the removal of the supports and members by a sliding movement parallel to the line of the stops.

6. An eliminator comprising a casing having an air passage therethrough, a plurality 110 of sets of removable members located in the passage, the members being spaced to provide a multiplicity of passages for the flow of air and serving to collect particles of foreign matter in the air current, and a plurality of independently removable sliding supports mounted in the top of the passage, each support carrying suspended therefrom one of the sets of members, the casing having an opening and closure therefor whereby 115 the supports may be removed while carrying the members.

7. An eliminator comprising a casing having an air passage therethrough and an opening in one side thereof, a closure for the opening, a plurality of rows of vertically supported chains located in the air passage, the rows extending transversely of the passage, supporting means extending transversely of 120

the passage and in alignment with the openings in the casing for normally supporting the rows of chains and for facilitating their removal from the casing.

In testimony whereof I have signed my
6 name to this specification.

HARRY N. MIDDLETON.
